L. SHOGREN

MECHANICAL DEVICE FOR SIMULATING WATER PROJECTION

Filed March 12, 1923

INVENTOR

L. Shogren
By Munro Leo,
ATTORNEYS

UNITED STATES PATENT OFFICE.

LEONARD SHOGAN, OF CHICAGO, ILLINOIS.

MECHANICAL DEVICE FOR SIMULATING WATER PROJECTION.

Application filed March 12, 1923. Serial No. 624,681.

To all whom it may concern:

Be it known that I, LEONARD SHOGAN, a citizen of the United States, and a resident of Chicago, in the county of Cook and State of Illinois, have invented a new and useful Improvement in Mechanical Devices for Simulating Water Projection, of which the following is a full, clear, and exact description.

10 My invention relates to improvements in mechanical device for simulating water projection, and it consists in the combinations, constructions, and arrangements herein described and claimed.

15 An object of my invention is to provide a mechanical device for simulating water projection which so closely resembles an ordinary stream of water that is practically impossible for an observer to detect the illusion, even though he is standing quite close to the device.

A further object of my invention is to provide a device of the type described which makes use of a piece of substantially transparent paper that is conical-shaped and corrugated, and which has novel means for oscillating the paper so that the paper closely resembles a stream of water.

20 25 30 A further object of my invention is to provide a device of the type described which is adapted to be placed in a show window so as to provide an attractive ornament for the window.

35 A further object of my invention is to provide a device of the type described which is adapted to have more than one artificial stream of water flowing from the device these streams being actuated by a common means.

40 45 50 A further object of my invention is to provide a device of the type described in which the exterior surface can be shaped in any manner desired, the stream of water issuing from any part of the device, such as from a lion's head or any other special shaped outlet.

A further object of my invention is to provide a device of the type described which may be readily used in show windows without the disadvantage of having the moisture collect on the show windows as is the case when real water displays are used.

55 A further object of my invention is to provide a device which is extremely simple in construction and in which the artificial

stream can be readily replaced, whereby the device will last a relatively long time.

Other objects and advantages will appear in the following specification, and the novel features of the invention will be particularly pointed out in the appended claims.

My invention is illustrated in the accompanying drawings forming part of my invention, in which—

Figure 1 is a front elevation of the device, showing one exterior form of the device,

Figure 2 is a section along the line 2—2 of Figure 3,

Figure 3 is a section along the line 3—3 of Figure 2,

Figure 4 is an enlarged detail view of a portion of the device,

Figure 5 is a plan view of the end of the artificial stream,

Figure 6 is a side elevation of a modified form of the device, and

Figure 7 is a plan view of another modified form of the device.

In carrying out my invention I provide a casing 1 and a supporting base 2. In the present form of the device I have shown the casing 1 and the base 2 as being constructed so as to closely resemble stone. It is obvious that the exterior surface of the device can be changed to any material desired, and that the shape of the device can also be changed.

The column 1 carries what apparently is a water receiving bowl 3 and also a lion's head 4. The stream of water that seems to be issuing from the mouth of the lion's head and flowing into the bowl 3 is in reality a piece of tissue paper 5 that is conical-shaped and corrugated, (see Figures 5). In Figure 3 I have shown the lower end of the paper 5 as being received in a wire loop 6 which is disposed beneath the top of the bowl 3 and is secured to the casing 1. The wire loop 6 keeps the lower end of the paper 5 in position, while the paper is being actuated by a means hereinafter described. It should be noted that the wire loop cannot be seen from the front of the device, since it is concealed by the bowl 3.

The means for oscillating the paper 5 is disposed in the interior of the column 1 and in the present form of the device is operated by an electric motor 7. The motor 7 is carried by a board 8. The board 8 is a part of a frame 9 which carries the paper actuating mechanism. In Figure 4 I have shown the

upper end of the paper 5 as being mounted in a sleeve 10, which in turn is frictionally held in a socket 11. The socket 11 has a shank 12 that is rotatably disposed in a sleeve 13. The collar 14 is rigidly secured to the shank 12 and bears against the upper end of the sleeve 13. The socket 11 and the collar 14 prevent longitudinal movement of the shank 12 with respect to the sleeve 13. 5 The sleeve 13 has an integral trunnion 15 which is pivotally disposed in an arm 16. It will be noted from Figure 3 that the arm 16 is carried by the frame 9 and positions the sleeve 13 so as to make the upper end of 10 the paper appear to be issuing from the mouth of the lion's head. The trunnion is held in place to the arm 16 by means of a nut 17.

I have found that by rotating the paper 5 through two or three revolutions about its longitudinal axis in one direction, and then through a like number of revolutions in the reverse direction, the paper will more closely resemble a real stream of water than if the paper were continuously rotated in one direction or just merely rocked about its longitudinal axis without making a complete revolution in either direction. The motor 7 actuates a mechanism for rotating the paper first through two or three revolutions in one direction and then through a like number of revolutions in the reverse direction, this mechanism being carried by the frame 9. This mechanism is clearly shown in Figures 2 and 3 and consists of a gear quadrant 18 that is rotatably mounted upon a stub shaft 19. The stub shaft 19 is carried by the frame 9. A crank 20 is also carried by the frame 9 and is mounted in a bushing 21. The crank 20 has a pulley 22 which is operatively connected to the motor 7 by means of a belt 23. The opposite portion of the crank 20 is slidably received in a slot 24 of the quadrant 18. From this construction it will be apparent that when the motor 7 is actuated it will cause the quadrant 18 to rock on the stub shaft 19.

In the present form of the device I have shown only one piece of paper 5, this piece of paper being actuated by the quadrant 18 by means of a flexible rod 25, a wire 26, and a second flexible rod 27, the rod 27 being rotated by means of a pinion 28 that is in mesh with the quadrant 18. The flexible rods 25 and 27 are in reality coil springs. When the quadrant 18 is actuated by the motor 7 it will rotate the paper 5 two revolutions in one direction and two revolutions in the other direction by means of the rods 25, 26, and 27.

From the foregoing description of the various parts of the device, the operation thereof may be readily understood. A light 29 is disposed in the bowl 3 and is connected 60 with the same source of current that actu-

ates the motor 7, whereby the light will illuminate the lower portion of the paper 5 when the motor is being actuated. The rotation of the paper first two revolutions in one direction and then two revolutions in 70 the reverse direction causes the lower portion of the paper to sway back and forth within the loop 6 so as to closely resemble the splashing of water as it breaks apart from the column of water that is issuing 75 from the mouth of the lion's head. The light 29 illuminates the lower portion of the paper, thereby making this portion of the stream more transparent, which is the case in a real waterfall. Moreover, the paper 80 has a swishing noise when it is being actuated which sounds like the fall of water. The light throws the shadow of the paper upon the front of the column 1, this shadow flickering so as to make the illusion more 85 realistic.

The device is especially adapted for show windows and provides an attractive ornament in the night time as the light illuminates the paper and a portion of the 90 front wall of the casing 1. The device may have various uses other than that shown in the present form of the device.

In Figure 6 I have shown a slightly modified form of the actuating mechanism, this form being identical with the form disclosed, except that the quadrant 18 is adapted to actuate a plurality of pinions 30, these pinions being each connected to a strip of paper 5. In other words, in the form of the device shown in Figure 6, the quadrant 18 is adapted to actuate five papers 5. It is obvious that this number can be increased indefinitely, since it is merely necessary to enlarge the quadrant 18 and add as many 100 pinions 30 as are desired. The pinions 30 are connected to flexible rods 31 which in turn extend from one side of the pinions. The quadrant 18 can be enlarged so as to form a complete gear, whereby a great many pinions 30 can be actuated by the same member 18.

In Figure 7 I have shown another modified form of the actuating mechanism, this mechanism being identical to the form shown in Figure 6 except that the pinions 40 which are actuated by the quadrant 18 have flexible shafts 41 extending from both sides of the pinions. In other words, each pinion is adapted to oscillate two flexible rods 31. Thus the five pinions in Figure 7 of the drawings are adapted to oscillate ten flexible rods 41. In this manner the number of artificial streams of water which are actuated by the same mechanism may be varied at will. The device is simple in operation, and closely resembles an ordinary stream of water when in operation.

It should be noted that the imitation stream of water need not be projected down-

wardly as disclosed in the present form of the device, but may be projected at any angle desired. It is also obvious that any number of streams may be actuated by the 5 same mechanism, these streams extending in any direction desired.

I claim:

1. In a device of the type described, a frame, a conical shaped corrugated piece of 10 tissue paper carried by said frame, and means for oscillating said paper about its longitudinal axis.

2. In a device of the type described, a frame, a conical-shaped corrugated piece of 15 tissue paper carried by said frame, means for oscillating said paper about its longitudinal axis, said means comprising a quadrant, a pinion actuated by said quadrant, a flexible rod operatively connecting said 20 pinion to said paper, and means for oscillating said quadrant.

3. A device for simulating a water projection comprising a casing having an imitation water outlet opening and an imitation 25 water receiving bowl, a member extending from said opening to said bowl and having the color of water, means operatively connected to said member adjacent to said opening for oscillating said member, and means 30 for loosely holding the lower end of said member, whereby an oscillation of said member will cause it to swish back and forth in the bowl to closely resemble a stream of projected water, and also to sound as falling 35 water.

4. A device for simulating a water projection comprising a casing having an imitation water outlet opening and an imitation water receiving bowl, a member extending 40 from said opening to said bowl and having the color of water, means operatively connected to said member adjacent to said opening for oscillating said member, and means for loosely holding the lower end of said member, whereby a rotation of said member 45 will cause it to swish back and forth in the bowl to closely resemble a stream of projected water, and also to sound as falling water.

5. In a device for simulating a water projection, a conical-shaped piece of paper and means for rotating said paper, whereby said paper is caused to flare outwardly at its lower end to closely resemble a stream of projected water. 50 55

6. In a device for simulating a water projection, a flexible member adapted to flare outwardly at its lower end and having the color of water, means for moving said member for causing said member to flare outwardly at its lower end to closely resemble a stream of projected water. 60

7. In a device for simulating a water projection, a flexible member adapted to flare outwardly at its lower end and having the color of water, means for moving said member for causing said member to flare outwardly at its lower end to closely resemble a stream of projected water, and means for illuminating said member. 65 70

8. A device for simulating a water projection comprising a casing, said casing having a water outlet opening, a basin carried by said casing, a member disposed between said opening and said basin, said member having the color of water, means for oscillating said member so as to cause said member to flare outwardly at its lower end, said means comprising a rack quadrant, a crank for oscillating said quadrant, means for rotating said crank, a pinion in mesh with said quadrant, and a flexible shaft extending from said pinion to said member. 75 80

9. A device for simulating a water projection comprising a casing, said casing having a water outlet opening, a basin carried by said casing, a member disposed between said opening and said basin, said member having the color of water, means for oscillating said member so as to cause said member to flare outwardly at its lower end, said means comprising a rack quadrant, a crank for oscillating said quadrant, means for rotating said crank, a pinion in mesh with said quadrant, a flexible shaft extending from said pinion to said member, and a light disposed in said basin for illuminating said member. 85 90 95

LEONARD SHOGRAN.
